DIE PRESS ATTACHMENT

Allan M. Cameron, Chicago, Ill., assignor to Cameron Can. Machinery Co., Chicago, Ill., a corporation of Illinois

Application July 25, 1940; Serial No. 347,448

4 Claims. (Cl. 113—50)

This invention pertains to die presses and more particularly to a device for clearing the formed articles from the path of the reciprocating die.

The beds, along which the work travels in presses of the single die or double die type adapted to stamp out and form can ends and analogous articles from sheets of tin plate, are customarily disposed at an inclination to the horizontal and the axes of the dies are disposed at a corresponding inclination, so that the stamped out products will fall rearwardly by gravity from between the dies. In the operation, however, of modern high speed presses in which the movable die reciprocates very rapidly, the time interval during which the formed article may escape from between the dies is exceedingly small. Consequently, any delay in the escape of the article occasioned by a tendency to stick to the die or by any other cause will result in the article being caught between the dies on the next operation, with ensuing damage to the work and possibly to the machine.

My present invention is designed to insure the escape of each formed article from between the dies by kicking it out transversely of the dies before the beginning of the descent of the movable die, thereby insuring against the possibility of damage either to the work or to the machine.

Another purpose of the invention is to provide a device of the character indicated which will be simple in construction, positive and reliable in operation and which will operate in timed relation with the die movements, regardless of the operative speed of the machine.

As illustrating the principles of my invention, I have disclosed in the accompanying drawings one practical embodiment thereof.

Referring to the drawings,

Fig. 1 is a side elevation of a press equipped with my invention;

Fig. 2 is a fragmentary plan section on the line 2—2 of Fig. 1;

Fig. 3 is a fragmentary section on the line 3—3 of Fig. 2; and

Fig. 4 is a fragmentary section on the line 4—4 of Fig. 2, but showing the movable die in raised position and the other movable parts in corresponding position, instead of in the lowered position of Fig. 2.

On the drawings, reference character 5 indicates the bed, 6 the frame, 7 the drive shaft, 8 the connecting rod, and 9 the cross-head of a die press of well known construction. High speed presses of this character are usually equipped with a clutch pin 11, a clutch pin throw-out

cam 12, and a control lever 13 connected by a link 14 with the cam 12. A delayed control for the clutch pin cam comprises a cam controlled lever 15 connected by a link 16 with an arm 17 rigid with the control lever 13. The circuit control switch 18 adapted to be actuated by the control lever 13 constitutes part of the control system for the press upon which it is here unnecessary to elaborate, since this system forms the subject matter of a co-pending application, Serial No. 355,937, filed September 9, 1940. The bed 19 upon which the stationary die 21 is mounted is carried upon the frame 6 in the usual manner, so that the table along which the work travels and the die are disposed in inclined position, the die being in axial alignment with the movable die 22 carried by the reciprocating cross-head 9. The press here illustrated, being of the double die type, comprises two movable dies 22 and a corresponding number of stationary dies 21. At each reciprocation of the cross-head, two can ends or similar articles are formed and stamped out, and upon the rise of the movable dies, these articles, which adhere to the movable dies, are freed therefrom (by the knock-out plungers 23 with which these machines are customarily equipped) and drop by gravity from between the dies in a rearward direction. To insure the escape of the formed articles from between the dies while the dies are disengaged, my present invention contemplates an ejector for each movable die which positively ejects or clears the formed articles from between the separated dies.

A work holding collar 24 slidably embraces each of the movable dies and is provided with a flange 25 by which the collar is attached to the cross-head 9 through bolts 26. Each collar is urged into the position shown in Fig. 4 by springs 27, and when the movable die enters the stationary die the collar yieldingly clamps the work around the dies between the collar and the table 19 under the influence of the springs 27. Upon each of these collars there is pivotally mounted upon a pintle 28 disposed parallel to the die axis, an arm provided at its free end with a cam follower in the form of a roller 31 and carrying in proximity to the roller an ejector in the form of a plate 32 extending inwardly from the arm toward the axis of the die. A coiled spring 33 normally urges each of the ejectors toward the axis of its die in a plane perpendicular thereto.

Upon the bed or table 19 there is adjustably mounted a pair of brackets 34, and in each bracket there is adjustably mounted an arm 35 projecting toward its respective set of dies and

carrying at its inner end a block 36 providing a cam or inclined face 37 disposed in the path of travel of the vertically reciprocating cam follower 31. The vertical position of these cams may be regulated by vertical adjustment of the brackets 34 upon loosening the fastening bolts 38, and the horizontal position of the cams may be regulated by adjusting the carrying arms 35 longitudinally in their brackets which are provided with slots for the reception of the bolts 39 by which the arms are locked in adjusted position.

At each operative or downward movement of the movable dies, the cam followers 31 will ride downwardly along the cam faces 37, thereby withdrawing the ejectors 32 from the path of the movable dies, permitting the desired cooperative action between the movable and stationary dies. Upon upward movement of the movable dies, the stamped and formed articles 41 will be carried upwardly with the movable dies and freed therefrom by the knock-out plungers 23. Simultaneously, as the followers 31 ride upwardly on the cams 37, the springs 33 will project the respective ejectors across the ends of the dies, so that they will engage and eject or kick out from between the dies the formed articles 41. This action of one of the ejectors is illustrated in Fig. 4.

It will be apparent from the foregoing that I have provided an attachment which positively ejects from between the movable and stationary dies, during their interval of separation, the articles which have been formed thereby, thus insuring against the possibility of damage which would result from failure of the formed articles to escape from between the dies during the brief interval in which the dies are separated one from the other. The attachment may obviously be applied to a single die press or a multiple die press, the principle involved being the same in each instance.

The structural details illustrated and described may obviously be varied within considerable limits without departing from the scope of my invention as defined in the following claims.

I claim:

1. In a die press, the combination of a recip-

rocable cross-head, a plurality of movable dies carried thereby, a plurality of stationary dies positioned to receive said movable dies, ejectors mounted on and movable with the movable dies and adapted to move transversely across the ends of the movable dies, and means for moving said ejectors across the faces of their respective dies in timed relation with the reciprocable movements of the cross-head for ejecting formed articles from the paths of movement of the movable dies.

2. In a die press, the combination with a stationary die and a reciprocatory die of a collar movable with the reciprocatory die, an arm pivotally mounted on said collar to swing across the face of the reciprocatory die in a path perpendicular to the path of movement of said die, an ejector carried by said arm, a spring for urging said arm across the path of the reciprocatory die, and a stationary cam in the path of said arm for withdrawing the ejector from the path of the reciprocatory die during the approach of said die toward the stationary die.

3. The combination with a die press including a stationary die and a reciprocable die cooperable therewith, of an ejecting device carried by and movable bodily with the movable die, a stationary cam positioned to withdraw the ejecting device from the path of the movable die upon downward movement of the die and device, and means for projecting said device across the face of said reciprocable die at right angles to the die axis upon upward movement of said die.

4. The combination with a die press including a stationary die and a reciprocable die cooperable therewith, of an ejecting device pivotally mounted upon and movable bodily with the movable die, a spring for projecting said device across the face of the movable die upon retractive movement of said die to eject an article formed by the dies from the path of movement of the movable die, and a cam positioned in the reciprocating path of said device for withdrawing the device from the path of the movable die upon the approach of the movable die toward the stationary die.

ALLAN M. CAMERON.
